(57) **CLAIM**

The ornamental design for a luminous unit for lighting, as shown and described.

DESCRIPTION

FIG. 1 is a perspective view of a luminous unit for lighting showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The even dashed broken lines shown in the drawings represent portions of the luminous unit for lighting, that form no part of the claimed design. The dashed-dot-dashed lines represent the boundary lines of the claimed design.
